US0D1057970S

(12) **United States Design Patent** (10) **Patent No.:** **US D1,057,970 S**
(45) **Date of Patent:** **** Jan. 14, 2025**

(54) **SKIN TREATMENT EQUIPMENT**

(71) Applicant: **Shenzhen Ulike Smart Electronics Co., Ltd.**, Shenzhen (CN)

(72) Inventor: **Lijun Tan**, Shenzhen (CN)

(73) Assignee: **Shenzhen Ulike Smart Electronics Co., Ltd.**, Shenzhen (CN)

(**) Term: **15 Years**

(21) Appl. No.: **29/902,549**

(22) Filed: **Sep. 14, 2023**

(30) **Foreign Application Priority Data**

Mar. 22, 2023 (CN) 202330141526.1

(51) **LOC (15) Cl.** **24-01**

(52) **U.S. Cl.**

USPC **D24/209**; D24/214

CLAIM

The ornamental design for a skin treatment equipment, as shown and described.

DESCRIPTION

FIG. 1 is a front perspective view of a skin treatment equipment, showing my new design;

FIG. 2 is a bottom perspective view thereof;

FIG. 3 is a rear perspective view thereof;

FIG. 4 is a rear view thereof;

FIG. 5 is a front view thereof;

FIG. 6 is a right side view thereof;

FIG. 7 is a left side view thereof;

FIG. 8 is a top view thereof; and,

FIG. 9 is a bottom view.

The broken lines in the drawings illustrate portions of the skin treatment equipment that form no part of the claimed design.

1 Claim, 9 Drawing Sheets
